FREQUENCY MULTIPLIER

Ludwig J. Mayer, Dayton, Ohio, assignor to the United States of America as represented by the Secretary of the Air Force

Application April 16, 1952, Serial No. 282,668

4 Claims. (Cl. 315—6)

(Granted under Title 35, U. S. Code (1952), sec. 266)

The invention described herein may be manufactured and used by or for the Government for governmental purposes without payment to me of any royalty thereon.

This invention relates to frequency multipliers and has as its object a frequency multiplier for the generation of ultra high frequencies in which the order of multiplication is relatively high and in which the direct to radio frequency current conversion efficiency is also relatively high.

The multiplier consists essentially of a velocity modulated or klystron frequency multiplier to which has been added a device, termed a phase shutter, to admit electrons to the buncher or velocity modulating element only during that part of the fundamental frequency cycle that will produce the most nearly ideal bunching of electrons from the standpoint of harmonic content.

The multiplier will be described in more detail in connection with two possible embodiments thereof shown in the accompanying drawings, in which—

Fig. 1 shows one embodiment of the invention in which the proper phase relation between the electrons admitted to the buncher and the fundamental frequency voltage at the buncher gap is obtained by introducing an appropriate phase shift between the phase shutter and the buncher;

Fig. 2 shows another embodiment of the invention in which the above mentioned proper phase relation between electrons and voltage wave is obtained by an appropriate spacing of the buncher and phase shutter; and

Figs. 3 and 4 graphically illustrate the operation of Figs. 1 and 2.

Referring to Fig. 1, cathode 1, buncher or velocity modulator 2 comprising resonant cavity 3 tuned to the fundamental frequency and velocity modulating gap G_V defined by grids 4—5, catcher 6 comprising resonant cavity 7 tuned to the desired harmonic and an energy extracting gap defined by grids 8—9, and anode 10 are similar to the corresponding elements of a conventional klystron frequency multiplier. To these has been added the phase shutter 11 consisting of cavity 12, resonant at the fundamental frequency, having a grid 13 which together with the emitting surface of cathode 1 defines a beam density modulating gap G_d . Input energy at the fundamental frequency is applied over transmission line 14 to coupling and phase shifting network 15 which supplies energy to cavity 12 by means of line 16 and coupling loop 17 and to cavity 3 by means of line 18 and coupling loop 19. Network 15 delays the phase of the energy applied to cavity 3 relative to that applied to cavity 12 by an amount to be defined later. This network may be any of the known types suitable to the frequencies involved such as a wave guide or coaxial transmission line. Voltage source 20 provides a bias potential for grid 13 while voltage sources 21 and 22 maintain grids 4, 5, 8 and 9 and anode 10 positive relative to the cathode.

The principle of operation of Fig. 1 is as follows: The

2

bias voltage E_{20} is greater than the cut-off voltage of grid 13 by the proper amount to prevent electron emission from the phase shutter 11 except during intervals of approximately $3/8\pi$ which are centered with respect to the center or $\pi/2$ points of the positive half-cycles of the voltage wave at the gap G_d . This is illustrated at (b) in Fig. 3. As a result one bunch of electrons 25 is emitted by the phase-shutter during each cycle of the fundamental frequency wave at G_d , as illustrated at (c) in Fig. 3.

The fundamental frequency wave across velocity modulating gap G_V is illustrated at (a) in Fig. 3. It is desired that the electrons from the phase-shutter, which form the bunches 25, pass through the gap G_V during that part of the fundamental frequency cycle extending from approximately $-\pi/4$ to $\pi/8$. This is accomplished in Fig. 1 by an appropriate phase delay, by phase shifter 15, of the voltage at G_V relative to that at G_d . Neglecting the transit time of the electrons between the two gaps the proper phase delay is $9/16\pi$ as shown in Fig. 3. If the transit time is not negligible the transit angle of the electrons should be added to $9/16\pi$ in order to arrive at the correct phase difference between the voltages at G_V and G_d . In any event the proper value should lie between $9/16\pi$ and $3/4\pi$.

Each electron in passing through gap G_V has its velocity modified in accordance with the amplitude and polarity of the voltage across G_V during its transit. Therefore electrons of various velocities are emitted from G_V and these collect in the drift space S to form sharp bunches of electrons 26 as shown in Fig. 3 (c). Electron bunches 26, in passing through the gap between grids 8 and 9, excite the resonant circuit of the catcher 6 which is tuned to a harmonic of the fundamental frequency. Since only one bunch 26 occurs for each cycle of the fundamental frequency electrons pass through the catcher gap only during the decelerating phase of the radio frequency voltage. The direct current to radio frequency current conversion efficiency is therefore high.

Fig. 2 shows another method of effecting passage of the electrons emitted by the phase shutter 11 through the gap G_V during the interval $-\pi/4$ to $\pi/8$ of the voltage wave at G_V . In this arrangement the buncher 2 is inverted with respect to its position in Fig. 1 and the resonant circuits of the buncher and phase-shutter are excited by energy of fundamental frequency applied thereto in the same phase by a suitable coupling network 15'. The desired phasing of the electrons relative to the radio frequency voltage across gap G_V is attained by making the distance d between gaps G_V and G_d of such value that the transit angle of the electrons between the two gaps equals $9/16\pi$. This relationship is shown graphically in Fig. 4. The required distance d is given approximately by the following expression.

$$d \approx 8.6 \times 10^6 \sqrt{\frac{E}{f}}$$

cm., in which

60 E = direct voltage of grids 4—5
 f = fundamental frequency

The theory underlying the design of the above described frequency multipliers is as follows: With a sequence of sharp electron beam pulses occurring at the fundamental frequency passing through the gap of the catcher the fundamental frequency as well as all harmonics can be excited with the same high electronic efficiency as long as the pulse width is small compared to a period of the harmonic in consideration. Neglecting all kinds of debunching and the finite transit time in the controlling gaps it is possible to create electron beam pulses of any desired sharpness in a distance p

from the buncher by a voltage rise across the buncher gap in accordance with

$$E_v = E_0 \frac{1}{\left(1 - \frac{a\sqrt{E_0}}{p} t\right)^2}$$

wherein

$$a = \sqrt{\frac{2e}{m}} \text{ and}$$

E_v = voltage across gap of buncher

E_0 = direct voltage at which electrons enter buncher

e = electron charge

m = electron mass

It would be difficult to create such a voltage rise periodically at a frequency high enough to be suitable as fundamental frequency in a multiplier for the generation of very high frequencies. However, the shape of an ordinary sine wave in the vicinity of the zero point preceding a positive half-cycle extending from $-\pi/4$ to $\pi/8$ is a good approximation of the above ideal shape for creating very sharp beam pulses. Hence an electron beam sent through a velocity modulation gap only during the above interval of the fundamental frequency wave at the gap will be phase-focussed nearly ideally to very sharp electron pulses which are able to excite harmonics of a very high order.

Restricting the current flow to the above defined intervals can not be done directly as it is only possible to open the current flow symmetrically around the positive maximum of the sine wave, or in other words, around $\pi/2$. Therefore, two control gaps or grids must be used, the voltages at which have to be apart in phase slightly less than $3/4\pi$ or which must be spaced apart so that the transit time between the two provides the required delay. The first control unit, the phase shutter 11, of Figs. 1 and 2, operates mainly as a density controlling device opening the gate for the electrons only during a phase interval of $3/8\pi$ which is symmetrical to $\pi/2$. After a phase delay of something less than $3/4\pi$, produced in Fig. 1 by the delay network 15 and in Fig. 2 by proper spacing of the buncher and phase-shutter gaps, the electron beam, now already pulsed, must be subjected to a velocity modulation which results in the formation at the catcher, after traversing the drift space, of much narrower bunches out of the relative wide bunches admitted to the velocity modulator. The narrow bunches are capable of generating harmonics of a high order in the catcher.

I claim:

1. A klystron frequency multiplier comprising a cathode, a buncher having a velocity modulating gap and a resonant circuit associated with said gap and tuned to a fundamental frequency, a catcher having an energy extracting gap and a resonant circuit associated with said gap and tuned to a harmonic of said fundamental frequency, and an anode, said cathode, buncher, catcher and anode being aligned so that electrons pass from said cathode through the gaps of said buncher and catcher in succession to said anode, means for applying energy at said fundamental frequency to the resonant circuit of said buncher whereby a sine wave of voltage of said fundamental frequency is established across the gap of said buncher, and means for blocking the flow of electrons from the cathode to the velocity modulating gap of said buncher except during that part of the cycle of the voltage across said gap extending approximately from $-\pi/4$ to $\pi/8$ radians, said last named means comprising a grid positioned between said cathode and the entrance to the gap of said buncher, a resonant circuit tuned to said fundamental frequency associated with said grid and cathode, means for applying energy at said fundamental frequency to said resonant circuit whereby a sine wave of voltage at said fundamental frequency is established

between said grid and cathode, means for biasing said grid negative relative to said cathode to such an extent that electron flow from said cathode to the gap of said buncher is cut off except during an angular interval of approximately $3/8\pi$ radians, relative to said fundamental frequency, which is centered with respect to the mid-point of the positive half-cycle of said sine wave of voltage between said grid and cathode, and means for timing the entry into said modulating gap of the electrons passed by said grid during said $3/8\pi$ interval so that said entry occurs during that part of the cycle of the voltage across said modulating gap extending from $-\pi/4$ to $\pi/8$ radians.

2. A klystron frequency multiplier comprising a cathode, a buncher having a velocity modulating gap and a resonant circuit associated with said gap and tuned to a fundamental frequency, a catcher having an energy extracting gap and a resonant circuit associated with said gap and tuned to a harmonic of said fundamental frequency, and an anode, said cathode, buncher, catcher and anode being aligned so that electrons pass from said cathode through the gaps of said buncher and catcher in succession to said anode, means for applying energy at said fundamental frequency to the resonant circuit of said buncher whereby a sine wave of voltage of said fundamental frequency is established across the gap of said buncher, a grid situated between the gap of said buncher and said cathode and close to the entrance to said gap, a resonant circuit connected between said grid and said cathode and tuned to said fundamental frequency, means for energizing said last-named resonant circuit at said fundamental frequency whereby a sine wave of voltage at said fundamental frequency is established between said grid and cathode, means for biasing said grid negative relative to said cathode to such an extent that electron flow from said cathode to the gap of said buncher is cut off except during an angular interval of approximately $3/8\pi$ radians relative to said fundamental frequency, which interval is centered with respect to the mid-point of the positive half-cycle of said sine wave of voltage between said grid and cathode, and means for delaying the phase of the sine wave of voltage at the gap of said buncher relative to the sine wave of voltage between said grid and cathode by an angle of approximately $9/16\pi$ radians.

3. A klystron frequency multiplier comprising a cathode, a buncher having a velocity modulating gap and a resonant circuit associated with said gap and tuned to a fundamental frequency, a catcher having an energy extracting gap and a resonant circuit associated with said gap and tuned to a harmonic of said fundamental frequency, and an anode, said cathode, buncher, catcher and anode being aligned so that electrons pass from said cathode through the gaps of said buncher and catcher in succession to said anode, means for applying energy at said fundamental frequency to the resonant circuit of said buncher whereby a sine wave of voltage of said fundamental frequency is established across the gap of said buncher, a grid situated between the gap of said buncher and said cathode, a resonant circuit connected between said grid and said cathode and tuned to said fundamental frequency, means for energizing said last-named resonant circuit at said fundamental frequency whereby a sine wave of voltage at said fundamental frequency is established between said grid and cathode, means for biasing said grid negative relative to said cathode to such an extent that electron flow from said cathode to the gap of said buncher is cut off except during an angular interval of approximately $3/8\pi$ radians relative to said fundamental frequency, which interval is centered with respect to the midpoint of the positive half-cycle of said sine wave of voltage between said grid and cathode, and means spacing the gap of said buncher from said cathode by such a distance that the electrons passing through said grid during the said $3/8\pi$ interval

pass through the gap of said buncher during that part of the cycle of the voltage across said buncher gap extending approximately from $-\pi/4$ to $\pi/8$ radians.

4. A klystron frequency multiplier comprising a cathode, a buncher having a velocity modulating gap and a resonant circuit associated with said gap and tuned to a fundamental frequency, a catcher having an energy extracting gap and a resonant circuit associated with said gap and tuned to a harmonic of said fundamental frequency, and an anode, said cathode, buncher, catcher and anode being aligned so that electrons pass from said cathode through the gaps of said buncher and catcher in succession to said anode, means for applying energy at said fundamental frequency to the resonant circuit of said buncher whereby a sine wave of voltage of said fundamental frequency is established across the gap of said buncher, a grid situated between the gap of said buncher and said cathode, a resonant circuit connected between said grid and said cathode and tuned to said fundamental frequency, means for energizing said last named resonant circuit at said fundamental frequency whereby a sine wave of voltage at said fundamental frequency is established between said grid and cathode, means for biasing said grid negative relative to said cath-

ode to such an extent that electron flow from said cathode to the gap of said buncher is cut off except during an angular interval of approximately $3/8\pi$ radians relative to said fundamental frequency, which interval is centered with respect to the midpoint of the positive half-cycle of said sine wave of voltage between said grid and cathode, means establishing an inverse phase relation between the voltage across the gap of said buncher and the voltage between said grid and cathode, and means spacing the gap of said buncher from said cathode by such a distance that the transit angle of the electrons thereacross is approximately $9/16\pi$ radians.
